UNITED STATES PATENT OFFICE.

ALBERT WILLIAM BOWERBANK, OF NEWCASTLE-UPON-TYNE, ENGLAND, ASSIGNEE,
BY MESNE ASSIGNMENTS, TO ELECTRICAL IMPROVEMENTS LIMITED, OF NEW-
CASTLE-UPON-TYNE, ENGLAND.

REHEATER FOR STEAM-TURBINE INSTALLATIONS.

Application filed October 11, 1920, Serial No. 416,302, and in Great Britain December 22, 1919.

This invention is for improvements in or relating to re-heaters for steam turbine installations and has for its object to provide means whereby the heating of the re-heater 5 can be regulated in accordance with the amount of steam passing through it.

According to the present invention a regulating device for a re-heater of a multiple-expansion turbine comprises in combination 10 heating means for the re-heater, a regulator for said heating means, and means to control the operation of the regulator proportionately or substantially proportionately with the turbine-load. By controlling the 15 regulator in this manner the purpose of the invention is obtained, that is to say the re-heater will be heated approximately in accordance with the amount of steam which it has to treat at any one time.

20 Conveniently, the regulator is a pressure-controlled device operated by the pressure of the steam passing to or from the re-heater, for example, by taking a small quantity of the steam from a suitable point on 25 the turbine, or from the re-heater, or the inter-connecting pipes between the re-heater and the turbine to operate said pressure device. The regulation of the heat for the 30 re-heater can be effected by controlling the supply of fuel and air, or fuel only, to fluid-fuel burners or burners of a similar character adapted to use other comminuted or flowable fuels.

In a preferred form of the invention, a 35 plurality of fuel burners are employed as a means to fire the re-heater and they are combined with a fuel-control device and means operatively connecting the device with the regulator.

40 A feature of the invention comprises a fuel-control valve or the like for each burner and a sliding member operatively connected with the regulator and with each of the control-valves characterized by the said sliding member being so arranged as to operate, during a follow-through movement, to close or open in succession the valves controlling the supply of fuel to the burners as the pressure falls or rises respectively. 45 The burners can conveniently be of the type for burning liquid fuel such as heavy hydrocarbons.

A further feature of the invention comprises a pressure-regulator in the form of a

piston-device in which steam is admitted to 55 one face of the piston and spring pressure is applied to the other face in opposition to the steam-pressure.

One preferred form of the invention will now be described in detail by way of example only, with the aid of the accompanying drawings, in which—

Figure 1 is an illustration in front elevation, largely diagrammatic, of one form of the apparatus according to the present invention, and is a partial section on the line 1—1 of Figure 2.

Figure 2 is a section on the line 2—2 of Figure 1.

Figure 3 is an enlarged view of the controlling mechanism, shown partly in Figure 1, for regulating the supply of fuel to the burners,

Figure 4 is a section on the line 4—4 of Figure 3, and

Figure 5 is a detail of an air-controlling device for burners.

Figure 6 shows diagrammatically a plant embodying several features of the invention, but it is not intended to represent the relative positions of the component parts or their construction as they appear in practice.

Like reference-numerals indicate like parts in the various figures of the drawings.

As shown in Figure 1, the high-pressure section of the turbine 6 is connected by means of a conduit 7 with the lower end of a re-heating chamber 10. The low-pressure section 8 of the turbine is also connected with the re-heating chamber at its upper end by means of a conduit 9.

In the form illustrated, the re-heater consists of a chamber 10 in which are disposed four banks of horizontal tubes 11, 12, 13 and 14 around and over which heated gases are 95 caused to circulate. To aid in the circulation, baffles 15 are provided so that the gases have to pass over the tubes in the direction of the arrows shown in Figure 2. The hot gases are then carried by means of a trunk 16 through a series of vertically-disposed tubes 17 contained in a casing 18 in the chamber 10. The gases pass from the trunk 16 downwardly through the upper ends of the tubes 17 and are exhausted through the lower ends of the tubes to a trunk 19 communicating with an outlet-flue or chimney-stack.

Steam admitted through the conduit 7 passes into headers 20 for the banks of tubes 12 and 14, through those tubes, headers 21, thence by way of conduits 22 to headers 23 for the banks of tubes 11 and 13, and finally passes through headers 24 to the outlet-conduit 9.

The gases for heating the chamber 10 are obtained with the aid of fuel burners 25 arranged in a flue 26 below the level of the chamber 10 and communicating with the back end thereof through an opening 27. In the example illustrated, four burners 25 are provided and the air-supply to them is conveniently heated by admitting air to the casing 18 through an inlet-port 51 at its lower end and extracting it from the casing and passing it to the burners through air-conduits 28. The air as it passes through the casing is heated by the gases which pass downwardly through the tubes 17. In front of the burners 25 there is preferably a perforated distributing baffle 29, and between the baffle 29 and the outlet 27 a feed-water heater 30 may conveniently be placed.

In order to regulate the heat supplied by the burners in accordance with the quantity of steam passing from time to time through the re-heating tubes, the following means is adopted: Suitable fuel such as gas or oil is admitted to the upper part of each regulating valve body from a main supply conduit 31, see Figures 3 and 4, from which it passes to each burner through a spring-loaded mushroom valve 32. In the form shown, the stem of each valve extends through the upper part of the valve body, and is combined with a spring 33 normally tending to keep the valve on its seat. The upper extremity of each valve-stem terminates in an anti-friction roller 34.

Supported above all the valve-stems is a sliding bar 35 carried in bearings 36 conveniently formed in the upper extremities of arms branching out and cast integral with the upper part of the regulating valve body. The bar is formed with a number of downwardly-projecting cam-surfaces 37, one for each valve-stem, and these projections are so disposed on the bar that an endwise movement of the latter towards the right in Figure 3 will bring the projections successively into engagement with the anti-friction rollers of the several valves so that the valve-stems are depressed, one after the other, thereby opening the valves and admitting fuel to the several burners. The cams 37 are of such length in their direction of movement that during the successive depression of the valve-stems, those first depressed will remain so during that full movement of the rod 35 which causes the opening of the valves.

65 The means for controlling movement of

the rod 35 comprises a bell-crank lever 38 pivoted at 39 in an extension from one of the regulating valve bodies, and connected at its free ends to the rod 35 and a piston-rod 40, respectively. The latter extends from a piston 41 working in a vertical cylinder 42 supplied with steam from the turbine through a steam-inlet 43 which admits steam to the upper face of the piston. Between the lower face of the piston and the lower end of the cylinder is a spring 44 tending normally to force the piston upwardly, and at the limit of its upward movement the piston will have moved the rod 35 to disengage the cams 37 from the rollers 34 to allow of the burner-valves to close and to shut off the fuel supply from the burners, with the exception of the last valve to operate which may be so arranged that it does not quite close but leaves a small opening to allow a sufficient quantity of fuel to pass to the burner for the purpose of keeping it a-light. The pressure of the steam admitted to the cylinder 42 will be proportional to and, technically stated, will be inversely proportional to the amount of steam passing through the re-heater and consequently the piston 41 will be depressed against the action of its spring in accordance with the steam pressure, thus opening one or more of the fuel-regulating valves in accordance with the amount of steam passing through the re-heater.

The air supplied to the burners for the combustion of the fuel may be controlled in a similar manner. For example, a piston rod 45 extending from the lower face of the piston 41 can be connected to a bell-crank lever 46, see Figures 5 and 6, which in its turn is connected to a sliding rod 47 similar to the rod 35 and operating similarly through tappet-rods 48 connected with hit-and-miss air-regulators 49, one for each burner. The movement of the air-regulating devices can be operated in accordance with the opening of the valves 32 and proportionately with the oil-supply thereto. In Figure 5 the part 50 represents the barrel of the burner, and 51' the fuel supply conduit disposed therein.

It will be therefore appreciated that in accordance with the amount of steam supplied to the turbine, in other words according to the pressure of the steam, more or less of the burners will operate for firing the re-heater. Thus, if the load is cut off the heat supplied to the re-heater will be cut down and vice versa. By this means damage to the re-heater by overheating of the parts, when only a small quantity of steam or no steam is passing through the steam-tubes, is avoided.

It is not essential to the invention that the feed-water heater 30 be employed in the position shown in Figure 2, although it is

preferably so employed, and serves somewhat to cool the hot gases passing from the burners to the re-heating tubes, and protects them from a too fierce heat should the burners be operating too freely.

What I claim as my invention and desire to secure by Letters Patent is:—

1. A regulating device for the reheater of a multiple expansion turbine comprising the combination with a plurality of fuel burners to heat the reheater, of a pressure-responsive regulator operating proportionately with the turbine-load in accordance with the pressure of the steam passing through the turbine, a fuel-control device for each burner, and means operatively connected with the regulator and with each of the control-devices, said means operating during a unidirectional movement to close or open in succession the control-devices of the burners as the turbine-load falls or rises respectively, substantially as described.

2. A regulating device for the reheater of a multiple expansion turbine comprising the combination with a plurality of fuel burners to heat the reheater, of a pressure-controlled regulator operated in accordance with the pressure of steam passing through the reheater, a fuel-control device for each burner, means operatively connected with the regulator and with each of the control-devices, said means operating during a unidirectional movement to close or open in succession the control-devices of the burners as the turbine-load rises or falls respectively, substantially as described.

3. A regulating device for the reheater of a multiple expansion turbine comprising the combination with a plurality of fuel burners for heating the reheater, of a fuel-control device for the burners, a control-device for the air supplied to the burners, a pressure-responsive regulator operating proportionately with the turbine-load in accordance with the pressure of the steam passing through the turbine, and means connecting the regulator with the fuel- and air-controlling devices to regulate the heating effect of

the burners in accordance with the turbine-load, substantially as described.

4. Re-heating apparatus for a multiple expansion turbine comprising in combination a reheat chamber having within it an air-heating device and a steam-chamber through which steam can circulate, a plurality of fuel burners for heating the air-heating device and the steam chamber, means to lead air from the air-heating device to the burners, a pressure-controlled regulator operated in accordance with the pressure of the steam passing through the reheat, a control-device for controlling the amount of fuel supplied to the burners, and means operatively connecting said control-device with the regulator, substantially as described.

5. The combination with a multi-section steam turbine, a reheat for the steam as it passes from one stage to the next, and heating means for the reheat, of a pressure-controlled regulator comprising a piston-device in which steam passing through the reheat is admitted to one face of the piston and spring pressure is applied to the other face in opposition to the steam pressure, and means connected with the regulator for automatically controlling the heat supplied to the reheat in accordance with the steam pressure operative on the piston, substantially as described.

6. A regulator device for the reheat between two sections of a multiple expansion turbine, comprising in combination, a plurality of liquid-fuel burners for heating the reheat, a fuel control valve for each burner, a pressure-controlled regulator operated in accordance with the pressure of the steam passing between the sections, and a sliding member operatively connected with the regulator and with each of the control valves, said sliding member operating during a unidirectional movement to close or open in succession the valves of the burners as the steam pressure falls or rises respectively.

In testimony whereof I affix my signature.

ALBERT WILLIAM BOWERBANK.
